**ELECTROLYTIC MARKING APPARATUS
INCLUDING STENCIL HOLDER**

Bruce W. Mayer, Cleveland Heights, Ohio, assignor to
The Electromark Corporation, a corporation of Ohio
Filed Feb. 7, 1963, Ser. No. 256,952
6 Claims. (Cl. 204—224)

My invention relates to electrolytic marking apparatus and particularly to the stencil holder and the stencil utilized with such apparatus.

An object of my invention is to provide an improved stencil holder adapted to reciprocate with the reciprocating member of automatic electrolytic marking apparatus.

Another object is the provision of a stencil holder adapted to hold a stencil in marking position intermediate the marking head and a workpiece that is to be marked.

Another object is the provision of a stencil holder adapted for ready insertion and removal of stencils in the replacement of stencils in the apparatus.

Another object is the provision of a stencil holder particularly adapted to accommodate to the reciprocating motion of a marking head in automatic or recurrently operated electrolytic marking apparatus.

Another object is the provision for an improved stencil particularly adapted for accommodation in my improved stencil holder.

Another object is the provision for a cooperatively reacting stencil holder and stencil constructed for use with the reciprocating head of electrolytic marking apparatus.

Other objects and a fuller understanding of the invention may be had by referring to the following description and claims, taken in conjunction with the accompanying drawing, in which:

FIGURE 1 is an elevational view of my improved stencil holder and stencil showing the head of the marker and associated parts in lower position;

FIGURE 2 is a view like that of FIGURE 1 except that it shows the head and associated parts in raised position;

FIGURE 3 is a view similar to FIGURE 2 by looking in the direction of the arrows 3—3 of FIGURE 2; and

FIGURE 4 is an enlarged perspective view of my improved stencil utilized with my stencil holder.

In views of the drawing, there is shown a reciprocating member 11 which is an elongated hollow member carried by a ram or arm of the apparatus so as to recurrently raise and lower the member 11. Included within the reciprocating member 11, but not shown, is a coil spring which urges an electrode holder carried by the holder 11 downwardly. An electrode holder 12 is electrically connected through member 11 with a flexible electrical wire 17 connected to a source of electrical energy.

A conductor rod or electrode 13 is secured to the holder 12 by means of a screw 14, the rod 13 extending downwardly from the holder 12 as shown. A pin 16 extends laterally from the holder 12 and out through a slot 15 in the wall of the reciprocating member 11. The inner-engagement of the slot 15 and pin 16 is such that a limited relative movement is permitted between the holder 12 and the member 11. The spring, not shown, within the member 11 resiliently urges the holder 12 downwardly and hence the pin 16 toward the lower end of the slot 15. The upper end of the slot 15 limits upward movement of the holder 12 and pin 16 relative to the member 11.

Mounted upon the metal conductor rod 13 so as to reciprocate therewith is a cylinder or reservoir 18 adapted to hold or accommodate a supply of electrolytic solution utilized in the electrolytic marking operation. This cylindrical reservoir 18 has a cap 18B closing the upper end of

2

the cylinder and accommodating the rod 13 which extends through the cap 18B and axially through the reservoir 18. The cylinder or reservoir also has a longitudinally extending rib 18A disposed along its length. The rib 18A provides a non-circular cross-sectional shape to the outside contour of the cylinder 18.

Secured to and carried by the lower end of the electrical conductor bar 13 is a porous carbon head or electrode member 19. Member 19 closes the lower end of the cylinder 18 and is sufficiently porous to permit electrolytic solution within the cylinder 18 to seep through the head 19. The head 19 is adapted to conduct electric current introduced thereto from the wire 17, holder 12 and conductor rod 13. As seen in the drawing, the carbon head 19 is shaped to have a reduced end portion and opposite shoulders as illustrated. An absorbent pad 20 is disposed over the reduced end of the head and held thereto by adhesive, bands or other suitable means. The pad 20 receives and holds electrolytic solution supplied thereto through the carbon head 19. The electrolytic solution in the pad 20 receives an electric charge from the head 19.

Slidably mounted on the cylindrical reservoir 18 is a stencil holder comprised of a cross-piece or saddle member 21 and dependent spaced side portions 22A and 22B extending downwardly therefrom. The cross-piece 21 has a hole extending therethrough which complements and accommodates the non-circular cross-section of the cylinder 18 having its rib 18A extending therethrough. Thus the cross-piece 21 may slide up and down relative to the reservoir 18 but cannot rotate around the axis of the reservoir 18. The hole in the cross-piece is such, however, that it is smaller in dimension than the head 19 so that the cross-piece 21 in its lowermost position rests upon and engages the top of the carbon head 19, as better seen in FIGURE 3.

The two spaced dependent side portions 22A and 22B are disposed substantially parallel to each other and accommodate therebetween the head 19 and pad 20. Disposed in opposite facing walls of the side pieces 22A and 22B are grooves 22C and 22D, respectively. These grooves are for the purpose of holding a stencil, such as the stencil generally indicated by the reference character 23, in operating position below the pad 20.

The stencil 23 is a rectangular piece of stencil paper, fabric or other material appropriately treated to operate and function as a stencil. It has formed therein the indicia of the mark to be impressed on the article or workpiece being marked. The making or preparation of the stencil and of the indicia perforation or their areas, are known and it is not necessary to here repeat. The main body of the stencil is of the film or sheet which is relatively flexible, that is, it will flex laterally when pressed or forcibly engaged on one side.

Extending along the main film portion 24 of the stencil 23 along opposite edges thereof are reinforced and relatively rigid edge portions 25 and 26, respectively. Preferably these edge portions 25 and 26 are formed by folded over additional paper or other material adhering to the edge portions so as to give additional thickness to the stencil along its opposite edge portions and to provide relative rigidity or stiffness to the edge portion. The edge portions may also be thickened or made more rigid by adding hardenable plastic material along the edges or by folding over the opposite edges to provide additional thickness and by coating such folded edges with hardenable flexible material to produce thickened and relatively rigid edge portions.

The stencil 23 is mounted to the holder by longitudinally sliding the edge portions 25 and 26 endwise into the respective grooves 22C and 22D so as to position the relatively flexible film portion 24 below the pad 20. It is

seen in the drawing the grooves 22C and 22D are disposed to incline to a common plane through the opposite grooves 22C and 22D. The grooves 22C and 22D extend upwardly and inwardly toward the axis of the head. Also the reinforced edge portions 25 and 26 are correspondingly inclined at such angles so as to readily fit within the grooves on sliding the stencil endwise into the grooves of the holder. The holder has a stop portion 22E at the rear end of the grooves 22C and 22D which limits the inward movement of the stencil 23 and thus assures the proper alignment of the indicia of the stencil film portion 24 with the article of the workpiece to be marked.

Supported on a suitable supporting base, such as a table top 29, is a carbon base electrode 27 which has a top surface upon which may be placed an article or workpiece 30 to be electrically marked. An electric wire or conductor 28 connected to a source of electrical energy is conducted to the carbon electrode 27 so as to conduct electric energy thereto. The wires 17 and 28 are of opposite polarity and so connected with a source of electrical energy that electrical energy of one polarity is conducted to the workpiece 30 and electrical energy of another polarity is conducted to the pad 20 whereby electrical energy flows through the stencil 23 to electrically etch the workpiece 30 by the electrolytic action of electrical energy in association with the electrolytic solution in the pad 20 and apply to the workpiece through the perforations or like solution-conducting area of the indicia in the stencil.

In the operation of the apparatus, a stencil bearing the appropriate stencilled indicia thereon is mounted to the holder as described so as to position the film portion 24 below pad 20. The member 11 is positioned upwardly as shown in FIGURE 2 and a workpiece 30 to be marked is placed upon the base electrode 27. The workpiece 30 is a metal object upon which a marking is to be made by an electrolytic etching operation. The electrolytic solution in the reservoir 18 saturates the pad 20 and electrical energy is supplied through wires 17 and 28 to provide the required electric potential. The apparatus is then operated so as to lower the reciprocating member 11 from the position shown in FIGURE 2 to that shown in FIGURE 1. This causes the head 19 and pad 20 to press downwardly and to cause the stencil 23 to be pressed by the pad 20 against the workpiece 30. At this time the electrical energy is applied so as to cause an electrolytic etching action to occur through the cooperation of the solution and electrical energy operating through the stencil. As the stencil 23 meets the resistance of the workpiece 30, the holder is raised to cause the cross-piece 21 or saddle to slide upwardly along the cylinder 18 from the position shown in FIGURE 2 to the position shown in FIGURE 1. To assure a firm pressure of the stencil against the workpiece, the pad 20 and head 19 are resiliently urged downwardly against the workpiece 30 by the coil spring within the reciprocating member 11 which urges the holder, rod 13, and parts carried thereby downwardly toward the workpiece 30. Relative movement between the holder 12 and member 11 is permitted by the pin 16 within the slot 15. As is apparent, pressure against the film portion 24 and the workpiece 30 and by the pad 20 which would otherwise tend to dislodge or disengage the opposite edge portions of the stencil from the grooves of the holder, is resisted by the angular inclination of the edge portions within the grooves. Thus the edge portions are so held that axially directed movement against the side of the stencil does not dislodge the stencil from the grooves in the holder.

It is thus seen by my improved holder and stencil, the stencil is always held in proper operative position, is not torn or dislodged, and is always in proper alignment for the marking operation. There is no side slippage nor other improper movement of the stencil along the surface of the workpiece. It has been found that rapid and auto-

matic recurrent etching operation of a series of workpieces may be accomplished through the use of my improved holder and with the improved stencil herein disclosed.

The present disclosure includes that contained in the appended claims, as well as that of the foregoing description.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and scope of the invention as hereinafter claimed.

What is claimed is:

1. An electrolytic marking tool combination including a holding device for holding a stencil in position relative to a reciprocal electrolytic marking head to engage a workpiece to be marked upon movement of the head downwardly to marking position adjacent the workpiece, comprising in combination a crosspiece carried by said marking head, said stencil having a body of relatively flexible material displaceable from the plane common to the opposite edge portion thereof upon the said marking head moving against the body of the stencil toward the workpiece, said cross-piece having an open space extending therethrough for accommodating said marking head and guiding reciprocal movement thereof relative to the cross-piece, spaced dependent pieces carried by said crosspiece and extending downwardly therefrom to accommodate the lower end of said head between said dependent pieces, said dependent pieces having oppositely disposed grooves, respectively, for accommodating opposite edge portions of a said stencil extending between said dependent pieces, said grooves being non-circular in cross-section and complementing the shape of non-circular edge portions of the stencil to limit rotation of the edge portions in the respective grooves upon displacement of the body of the stencil by the marking head moving toward the workpiece, said grooves being inclined upwardly and inwardly toward each other to hold said edge portions of the stencil angularly to a horizontal plane extending between the openings of the said grooves whereby said stencil is restrained against withdrawal from said grooves by downwardly exerted force on the stencil intermediate of said grooves by said head moving toward said workpiece, said grooves being open at one end of said dependent pieces, respectively, to permit the stencil to be moved in and out of position between the dependent pieces by sliding the edge portions, respectively, longitudinally of said grooves, said grooves being closed at the opposite end of said dependent pieces, respectively, to limit the movement of said edge portions in said grooves and to fix the position of the stencil between said dependent pieces, said holding device being movable upwardly relative to the said head upon said stencil meeting the resistance of a said workpiece in the downward movement of said head toward the workpiece.
2. An electrolytic marking tool combination including a holding device for holding a stencil of a marking tool reciprocal to and from a workpiece to be marked, said tool having a head and a pad carried thereby, said pad being adapted to hold electrolytic solution electrically energized for etching of the workpiece through said stencil, said stencil having relatively stiff opposite edge portions of non-circular cross-sectional shape and being relatively flexible therebetween and subject to displacement from a plane through said edge portions upon said head being moved thereagainst toward a said workpiece, said holding device comprising a saddle member having a base portion adapted to be carried by said tool to be moved with the head toward and away from a said workpiece, said saddle member having spaced side portions carried by said base portion to move therewith, said side portions being adapted to be disposed on opposite sides of said head and pad, said side portions hav-

70
75

ing spaced grooves adapted to be accommodated opposite edge portions of said stencil to hold the stencil extended between the said side portions and in juxtaposition to said pad, said grooves being non-circular in cross-section to complementarily interfit with said opposite edge portions of said stencil to hold the respective edge portions against rotation therein, said grooves being disposed to hold said edge portions, respectively, in planes offset from a common plane through the opposed openings of said grooves, respectively, to retain the said edge portions in said grooves against withdrawal through the said openings upon application of force on said stencil by said head moving toward a said workpiece, said grooves being open at one end to permit said edge portions to be slid endwise into said grooves, respectively, and being closed at the opposite end to limit movement of the said edge portions inwardly of the grooves, said holding device holding a stencil having its opposite edge portions in said grooves in juxtaposition to said head to be placed in engagement with a said workpiece for the etching thereof upon movement of the head to the workpiece.

3. An electrolytic marking tool combination including a holding device as defined in claim 2 and including lost motion between the saddle member and tool to permit the said head to proceed toward the workpiece after movement of the holding device toward the workpiece is resisted by engagement of the workpiece with the stencil carried by the holding device.

4. The combination of a holding device adapted to be carried by a reciprocal electrolytic marking tool and a stencil carried by the holding device to be movable therewith to position the stencil in juxtaposition to the solution-carrying pad of the head of the tool and to position the stencil in etching location adjacent the workpiece upon movement of the tool to the workpiece, said stencil having opposed inclinable edge portions and said holding device having opposed inclined grooves for accommodating said edge portions, respectively, to dispose the said stencil intermediate said pad and a said workpiece to which said tool is moved, said edge portions and grooves being non-circular in cross-section and interfitting to resist rotation of an edge portion in a groove upon lateral pressure on the stencil, said edge portions and grooves being complementarily offset from a common plane through the said grooves to resist withdrawal of the edge portions laterally from the grooves upon axial movement

of the stencil intermediate of the edge portions relative to said grooves, said grooves being open at corresponding ends to facilitate sliding insertion of the respective edge portions therein.

5. An electrolytic marking device including in combination a reciprocal electrolytic marking tool movable toward and away from a workpiece to be marked, a tool having an electrolytic-solution carrying head, and a stencil holder carried by said tool and having spaced side portions disposed on opposite sides of said head, said side portions having parallel stencil-engaging portions adapted to engage and hold opposite parallel edge portions of a stencil extending therebetween intermediate said head and a workpiece to be marked, said stencil-engaging portions of the stencil holder each having opposite parallel walls adapted to engage opposite sides of a respective edge portion, said walls being angularly inclined from a common plane through both the stencil-engaging portions to hold the stencil edge portions against disengagement from each stencil-engaging portion in direction toward the other stencil-engaging portion, said stencil-engaging portions being open at corresponding ends to readily permit the stencil edge portions of a stencil to be moved endwise into place in the stencil-engaging portions.

25 6. A stencil holder as defined in claim 5 and in which stop means are included therein to limit the endwise movement of the stencil edge portions in the said stencil-engaging portions.
